CRUSHING AND PULVERIZING MACHINE

Edwin E. Elzemeyer and Henry C. Griesedieck,
Webster Groves, Mo., assignors to American
Pulverizer Company, St. Louis, Mo., a corpora-
tion of Missouri

Application November 9, 1931. Serial No. 573,920

1 Claim. (Cl. 83—11)

This invention relates generally to crushing and pulverizing machines and has more particular reference to crushing or pulverizing apparatus of the rotary hammer or ring type.

5 Our invention has for its chief object the provision, in a machine of the type stated, of a pivotally swingable grinding surface and readily operable means for conveniently, efficiently, and positively shifting the grinding surface adjust-
10 ably relative to the hammer mechanism of the machine, as may be desired in the particular grinding or pulverizing operations being carried on.

And with the above and other objects in view, 15 our invention resides in the novel features of form, construction, arrangement, and combination of parts hereinafter described and pointed out in the appended claim.

In the accompanying drawings (two sheets)—
20 Figure 1 is a side elevational view, partly broken away and in section, of a crushing or pulverizing machine embodying our invention;

Figure 2 is a fragmental side elevational view of the lower portion of the machine; and

25 Figure 3 is a fragmental half rear-elevational view, partly broken away, of the lower portion of the machine.

Referring now more in detail and by reference 30 characters to the drawings, which illustrate a preferred embodiment of our invention, A designates the base casing-section or frame of a crushing or pulverizing machine, which includes op- posed upstanding side-walls 1, a rear end-wall 2, and a front end-wall 3, and B designates a re- 35 movable cover or upper casing-section including a feed hopper 4.

C designates the hammer mechanism of the machine, which is disposed for rotation between the casing-sections A, B, and preferably, in the 40 present instance, includes a shaft 5 journaled in bearings 6 supported by means of suitable brackets 6' projecting from the casing side-walls 1, to which shaft is suitably keyed a carrier 7 having pivotally connected thereto for rotation therewith 45 a plurality of hammer assemblies each including a pair of bails 8 connected by a pin 9, each pin 9 supporting a cylindrical hammer 10 mounted loosely in the bail for rotation with and relatively to, the carrier 7, as more fully and particularly 50 disclosed in our co-pending application, for Letters Patent for Pulverizing machine, filed Decem- ber 20, 1930, Serial No. 503,749, to which refer- ence is made.

D designates generally the main grinding-surface 55 of the machine, which is composed, in the

present instance, of a more or less tangent breaker plate 11 leading from a fixed feed-plate 12 disposed in the hopper 4, the plate 11 at its lower margin being preferably slightly curved or arcuate to smoothly meet an adjoining series of transversely arcuate contiguous concaves or grinding plates 13, each of the plates 11, 13, longitudinally extending substantially the width of the casing-section A between the side-walls 1 thereof and being suitably removably attached to, and supported by, a cradle or backing-frame E, sometimes called a plate-cage.

The cradle or cage E, in turn, includes a body- section 14 having depending side-marginal flanges 15 enlarged at their respective upper ends 70 to provide hubs 16 for connection, for pivotally supporting the cradle or cage E, with a transverse shaft 17 supported by and between the casing-walls 1 adjacent the upper forward corner thereof beneath the hopper 4.

So supported, the cradle body-section 14 swing- ably depends in a generally concave or downward curvilinear direction rearwardly under the ham- mer-mechanism C for adjustable movement of the supported grinding surface D, as a whole, 80 relatively both to the paths of the hammers 9 and to the casing-section A.

On its rearward end, the cradle-body 14 car- ries a detachable cradle-end section or so-called cage-extension 18 adapted to support a sectional 85 plate 13 and provided at its opposite longitudinal ends with depending forwardly oblique arms 19 each having a forwardly curved slot 20 centered on the rod 17 for working over studs 21 suitably projecting from the adjacent casing-walls 1 for 90 guiding the cradle E in shiftable movement.

The described grinding surface D and cradle E are more fully and particularly described in our co-pending application for Letters Patent for Pulverizing machine, filed November 16, 1930, 95 Serial No. 494,659, to which reference is hereby made. Hence further description thereof is here omitted.

The grinding clearance between the hammers 10 and plates 11, 13, may hence be suitably altered 100 or adjusted by shifting the cradle E, as conditions may require, which adjustment is accomplished in the present instance by mechanism now to be described.

Such mechanism includes registering apertured 105 lugs or bosses 22 dependently formed in cradle- intermediate position on the cradle-body flanges 15 parallel with the cradle-supporting rod 17. Outwardly projecting from the casing side-walls 1, are bosses 23 provided with oblong slots 24 110

for registration with the apertures of lugs 22, which slots 24 may be on an arc centered on the rod 17. Preferably, however, as in the present instance, the slots 24 are tangent to such an arc, as best seen in Figure 1.

Supported in and through the lugs 22, is a rod 25 having its respective ends presented through the slots 24 and terminating in threaded portions engaged by suitable retaining members 10 or nuts 26, as best seen in Figure 3.

Disposed on opposite sides of the casing A and journaled on the projecting ends of the rods 25 intermediate the nuts 26 and the bosses 23 for normal frictional engagement therebetween, are eyes or hubs 27 formed on the forward ends of respective elongated draw-bars or cradle-shifting members F, each of which extends, approximately tangentially to an arc centered on the pivot-rod 17, in upward rearward inclined direction through a suitable slot 29 provided in the respective bearing-bracket 6' and endwise terminates in a screw-end or threaded portion 30 longitudinally shiftably engaged in and through a suitably apertured lug or bracket 31 outwardly projecting from the upper rear corner of the respective casing-side wall 1, suitably threaded members or nuts 32 engaging the screw-ends 30 for bearing on the opposite sides of the respective lug 31 for adjustably retaining the draw-bar F in shifted position therein.

As best seen in Figures 1 and 3, a pair of suitably spaced anchor-bolts 34, provided with eyes 35 engaging the rod 25, are projected endwise therefrom through the casing front-wall 3 and have threaded thereon suitable nuts 36 adapted for impingement upon the wall 3 for opposing the pull of the draw-bars F on the rod 25 for initially tensing the straps and thus rigidly supporting the grinding surface structure for most effectively preventing undue vibration in the machine when the latter is in use.

In use and operation, on loosening the nuts 26 on the rod 25, and if necessary or desirable also shifting the nuts 36 for slackening the anchor-bolts 34, the cradle E may with ease and facility be adjustably swung towards or from the hammer mechanism C by suitable manipulation of the nuts 32 on the draw-bars F for shifting the same in the casing-supported lugs 31.

50 In such manner, adjustments of the grinding-surface D may be effected in a simple, facile, and convenient manner, which, being accomplished, the grinding-surface D may be secured in its respective adjusted position by jamming

the nuts 32 of the draw-bars F on the anchor-lugs 31, tightening the nuts 26 onto the eyes 27 of the bar 28 for, in turn, gripping the rod 25 on the casing A, and then taking up the slack of the anchor-bolts 34.

It will be seen that the pulverizing or crushing of a product by a machine equipped with our adjustable grinding-surface may be controlled with certainty and exactitude, and that variations in the grindability of material fed to such a machine may with nicety and proficiency be compensated for by precise manipulative adjustments of the grinding surface.

It will be understood that changes and modifications in the form, construction, arrangement, and combination of the several parts of the machine may be made and substituted for those herein shown and described without departing from the nature and principle of our invention.

Having thus described our invention, what we claim and desire to secure by Letters Patent is,—

In a machine of the class described, in combination, a casing having opposed side walls, a shaft supported by and extending transversely between said walls, a grinding-concave within the casing, side marginal flanges on the concave engaging said shaft for pivotally supporting the concave at an end for swingable movement, said walls being provided with registering slots tangent to an arc centered on said shaft, means for adjustably supporting the concave at its free end relatively to the casing, said means including bosses depending from the concave-flanges and apertured in parallelism with said shaft, a transverse rod having its opposite end-portions disposed through the apertures of said bosses and projecting for movement in said slots, apertured lugs fixed on the casing side walls in spaced relation to and disposed in a plane spaced upwardly from the horizontal plane of said slots, draw-bars disposed obliquely along the side walls of the casing in a plane also tangent to an arc centered on said shaft, said bars having connection at an end with said rod and disposed adjacent their other ends for longitudinal shiftable movement in and through said lugs, and securing members for engaging the bar and lugs, and means including an anchor-bar having engagement with said rod and extending in opposition to the draw-bar for engagement with the front wall of the casing for tensioning the concave against vibration.

HENRY C. GRIESE DIECK,
EDWIN E. ELZEMEYER.
